SHUTTLE FOR CARPET LOOMS

Isaac B. Bassindale, Grasscroft, England

Application February 21, 1947, Serial No. 730,044
In Great Britain February 16, 1946

Section 1, Public Law 690, August 8, 1946

3 Claims. (Cl. 139—124)

1

This invention relates to shuttles for forming the selvedge in a carpet being woven in a carpet loom employing one or more selvedge shuttles.

As at present generally constructed a shuttle for this purpose is relatively small and only capable of holding a small yarn package. Consequently the yarn, hereinafter for convenience referred to as the selvedge cord, is quickly exhausted, thus necessitating frequent stopping of the loom to enable replenishment of the cop and piecing up of the selvedge cords to be effected.

The frequent stoppages adversely affect the productive capacity of the loom. Further, in shuttles as at present constructed the selvedge cord is wound on a small metal spool which revolves in one fixed and one spring-loaded pivot bearing in the shuttle. The spring on the pivot bearing acts on the spool of selvedge cord as a brake and is adjustable to regulate the tension on the cord which is drawn from the outer side of the spool. It is obvious that when the spring is adjusted for a full spool the tension must vary as the spool diminishes in diameter due to the pull of the cord being exerted at a less radius. The variation in tension on the cord tends to produce an irregular edge on the carpet being woven.

The present invention overcomes these disadvantages by providing a selvedge shuttle which is capable of receiving a much larger yarn package than has heretofore been possible, e. g., a solid wound cop, that is a cop consisting entirely of yarn tightly wound without the use of a pinc or tube, in which the selvedge cord, being drawn from the centre of the cop, can be drawn off until the cop is exhausted without any variation in the tension which remains constant throughout the operation.

A selvedge shuttle according to the invention, having a curved body of large size to receive a solid wound cop, embodies an adjustable cord tension element, a spring-influenced element for putting a drag on the cord being drawn off from the cop whereby to prevent the formation of snarls, and means for preventing the formation of an undesirably large loop of surplus cord outside the shuttle.

Description will now be given of a practical construction of shuttle according to the invention, reference being made to the accompanying drawings in which Fig. 1 is a side view of a shuttle; Fig. 2 is a plan of the shuttle shown in Fig. 1, part of the upper wall being broken away to expose the interior; Fig. 3 is a sectional view through the line III—III of Fig. 1; Fig. 4 is a perspective view, drawn to a smaller scale, of the shuttle with the cover plate in position.

The same reference characters indicate corresponding parts in the several figures of the drawings.

2

Referring to the drawings, the shuttle comprises a body 10 of arcuate shape in plan, formed at its front end with a tapered and slightly turned-up nose 11, and being rounded at its rear end 12. The shuttle body 10 presents in its outer curved side an open-sided compartment 13, the base of the body forming the floor 14 of the compartment 13, presenting a plane flat surface upon which the shuttle slides in the shuttle race, while the top of the shuttle body, forming the roof 15 of said compartment, is parallel with the bottom or base from the rear of the shuttle to a point approximately two-thirds of the length of the shuttle when it is inclined downwardly towards the base 14, whereby to produce the aforesaid tapered nose 11. The tip of said nose is curved slightly upwards, see Figs. 1 and 4, for a purpose later to be explained. A recess is formed in the top of the shuttle for engagement of the front shuttle driver, the recess being indicated at 16 in Fig. 4 and in dotted lines in Fig. 1.

That portion 13^a of the compartment 13 for receiving the cop, indicated at C, is deeper than the remaining portion, the deeper portion 13^a extending from the rounded rear end 12 of the shuttle body 10 to a point just short of the mid-horizontal centre line of the arcuate shuttle body, as viewed planwise, and is adapted to receive a large solid wound cop C of selvedge cord, the walls 14 and 15 and, if desired, the side wall 17 of the deep compartment 13^a being grooved or serrated as at 18 to facilitate retention of the cop C in the shuttle. For convenience, this portion of the compartment will hereinafter be referred to as the cop compartment.

Located in the shallow part of the compartment 13, hereinafter for convenience referred to as the tension compartment, at mid-position of the shuttle body, is an adjustable tension element 40 including a thin metal plate 19 bent angularly upwards at one end to provide a vertical flange 20, which extends coplanar with the edge 13^b of the side wall of the compartment 13, said wall and the flange 20 providing an end wall for the cop compartment 13^a. At its opposite edge the metal plate 19 is formed with an upturned portion 21 to provide a guide for the selvedge cord in its passage beneath the tension member, and to prevent the selvedge cord working out from under the pressure plate of the tension member. A relatively thick metal plate 22, hereinafter referred to as the base plate, is fitted on top of the thin plate 19 and the two plates are secured in the shuttle by any appropriate means, e. g., by riveting, as indicated at 23, Fig. 1.

The base plate 22 is formed with a vertical bush 24 upon which is loosely mounted a metal pressure plate 25, preferably boat-shaped or elliptical, as shown in Fig. 2, and restrained against turning movement relatively to the bush by a

peg 26, Fig. 3, projecting from the base plate 22 and engaging the pressure plate 25. The peg 26 is formed at its upper end with a conical point adapted to engage in a conical-ended recess in the pressure plate 25 whereby to provide a hinge for the pressure plate 25 when said pressure plate is lifted to permit passage of the selvedge cord thereunder. The pressure plate 25, is held in yielding contact with the base plate 22 by a compression spring 26^a encircling a stud bolt 27 projecting through the bush 24 and formed at its upper projecting end with a head 28 affording abutment for the spring 26^a and being screw-threaded at its lower end where it is furnished with a screw-threaded locking nut 29, whereby the compression of the spring 26^a may be regulated. The lower end of the stud bolt 27 is screwed into the thick side wall of the shuttle 10 in which a recess 30 is formed to accommodate the locking nut 29. The base plate 22 is also furnished with a guide hook 31 and a guide eye 32.

Located in the tension compartment 13, in proximity to the tension device, is a serrated roller 33 journaled in the bifurcated ends of a spring plate 34 fixed by screws to the side wall of the tension compartment. The spring plate 34 is formed with an upstanding tongue 35 having a groove therein to serve as a guide to ensure that the selvedge cord C' passes directly below the centre of the serrated roller 33.

A passage 36 is formed in the side wall of the tension compartment 13 to provide communication with the cop compartment 13^a and a guide eye 37 is provided in the tension compartment adjacent to the opening of the aforesaid passage 36 into the tension compartment 13.

A tension spring 38 is secured at one end to a screw 39 adjacent to the end of the tension compartment remote from the tension device, the opposite end of the spring 38 being provided with an eye 40.

In the upper wall or roof 15 of the tension compartment 13 there is formed an eye 41 for passage of the selvedge cord.

In the preparation of a shuttle for use, the free end of a solid wound cop of selvedge cord is threaded through the passage 36 in the wall of the tension compartment 13 prior to the cop C being pressed into the cop compartment 13^a. The loose end of the selvedge cord is then threaded through the guide eye 31 adjacent to the end of the passage 36, then led through the slotted guide 35 and beneath the serrated roller 33, under the spring-influenced pressure plate 25 of the tension device, through the adjacent guide hook 31 and guide eye 32, then through the eye 40 of the tension spring 38 and finally through the eye 41 in the wall of the shuttle. The pressure of the spring 26^a of the tension device is regulated to apply the desired degree of tension to the selvedge cord.

In the operation of the shuttle, the selvedge cord is drawn off from the centre of the cop and the slight drag imparted to the selvedge cord by the spring-influenced serrated roller 33 prevents the formation of, or straightens out, any snarls in the selvedge cord.

The tension of the coiled spring 38 serves to draw any surplus selvedge cord into the tension compartment 13^a, thereby avoiding the formation of an undesirably large loop of selvedge cord out-

side the shuttle which might become trapped between the shuttle and the shuttle race.

The opening in the compartments 13, 13^a is closed by a spring plate or cover 42 (Fig. 4) having a curl at one end and adapted to engage a hinge pin 43 mounted in the top and bottom walls of the shuttle adjacent to the rear end 12 of the cop compartment 13^a, while the opposite end of the plate or cover 42 is sprung below a retaining pin 44 located adjacent to the front end of the tension compartment 13^a.

The tapered and slightly turned-up formation of the nose 11 of the shuttle facilitates entry of the shuttle through the loop of weft carried by the needle which is formed in its lower surface with a groove or recess at the place where the shuttle enters the loop of weft, while the curved formation of the shuttle facilitates passage of the loop of weft along the body of the shuttle until it drops off the blunt end 12 and is subsequently caught by the selvedge cord.

As the amount of selvedge cord contained in a shuttle as described is many times the amount of selvedge cord contained in even the largest size of shuttle as at present constructed it follows that the stoppages of a loom for replenishment of the selvedge cord are much less frequent than heretofore necessary and consequently the productive capacity of the loom is increased.

A shuttle constructed as described is advantageous for use with a shuttle motion as described in the specification of my copending application for Letters Patent Serial No. 730,043, filed February 21, 1947.

What is claimed is:

1. A selvedge shuttle for a carpet loom, having an arcuate body formed with an open sided cavity to receive a cop, and embodying an adjustable cord tensioning element, a spring-influenced element for putting a drag on the cord being drawn off from the cop whereby to prevent the formation of snarls, and means for preventing the formation of an undesirably large loop of surplus cord outside the shuttle.

2. A selvedge shuttle as claimed in claim 1 having an arcuate body having a compartment to receive a cop, and an adjoining compartment, a tension element in said adjoining compartment comprising a thin metal plate flanged to provide guide means, a relatively thick metal base plate superposed on said first-mentioned plate and formed with a projecting bush, a metal pressure plate strung on said bush, spring means for holding said pressure plate in yielding contact with said base plate, an anti-snarling element comprising a serrated roller and a spring plate providing a journal for said roller and having guide means to direct the selvedge cord under the centre of said roller, and a tension spring anchored at one end of said second compartment and having at its free end a guide eye to receive the selvedge cord in its passage to the delivery eye of the shuttle.

3. A selvedge shuttle as claimed in claim 1, having a compartmented body of arcuate shape in plan, formed at its front end with a tapered nose upwardly curved at its tip, said body being rounded at its rear end, and having a recess in its top for engagement by the front shuttle driver of the loom.
